5 Claims. (Cl. 121—46.5)

1

This invention relates to automatic gun control systems of the type responsive to hydraulic pressures and in particular to a novel and improved hydraulic follow-up system responsive to a manual control device and including a pressure control valve mechanism adapted to control generated pressures and a pressure responsive servomotor for actuating the driving and computing mechanisms.

This application is a division of the copending application of Newell et al., Serial No. 534,330, filed May 5, 1944, for Automatic Gun Control System.

An object of the invention is to provide a valve mechanism of the above type having novel and improved details of construction and features of operation.

Other and more specific objects will be apparent as the nature of the invention is more fully disclosed.

In accordance with the present invention a pair of pressure control valves are actuated in accordance with the position and rate of movement of the gunner's control handle to vary hydraulic pressures in a manner to produce control pressures corresponding to the desired rates of train and elevation respectively. These control pressures are applied to the pressure responsive servomotors which are adapted to control rate input linkages of an automatic computing mechanism. The pressures may also be applied to precessing force motors which apply precessing forces to a gyroscope as more fully set forth in the patent application above identified.

Although the novel features which are believed to be characteristic of this invention are pointed out more particularly in the claims appended hereto, the nature of the invention will be better understood by referring to the following description, taken in conjunction with the accompanying drawings in which a specific embodiment thereof has been set forth for purposes of illustration.

In the drawings:

Fig. 1 is a section through a hydraulic pressure control valve block embodying the present invention showing the control handle and the hydraulic connections;

Fig. 2 is a side elevation of the manual control handle and support therefor;

Fig. 3 is a vertical section through the control handle and support taken along the line 3—3 of Fig. 1;

Fig. 4 is a partial horizontal section taken on line 4—4 of Fig. 1; and

2

Fig. 5 is a diagrammatic view of the follow-up system showing the pressure responsive servomotors in section.

Certain specific terms are used herein for convenience in referring to various details of the invention. These terms, however, are to be given an interpretation commensurate with the state of the art.

Pressure control valves

Referring to the drawings more in detail, the pressure control valves are shown as mounted in a valve block 157. Control handles 155, adapted to be actuated by the gunner, are shown as mounted on a horizontal shaft 100 which is pivoted in a bracket 156 for rotation about a horizontal axis and carries an arm 1, Fig. 3, which is attached by a pivoted link 2 to a slidable rod 3 which is located within the bracket 156 and carries a pair of collars 4 which actuate an arm 5 carried by a shaft 6. The shaft 6 in turn carries an arm 7 which is connected by a link 8 to a valve plunger 9 in a manner such that the valve plunger is shifted from a central position an amount corresponding to the rotational movement of the handles 155 about their horizontal axis. The position and rate of movement of the valve plunger 9 controls the operation of an elevation pressure control valve 10. The rotational position of the handles 155 corresponds to the elevation rates which control the position of the pressure responsive servomotor to be described later. These rates may also be applied to an elevation precessing motor of a gyroscope to cause the gyroscope to precess at a corresponding rate. The position and rate of movement of the plunger 9 controls and is a measure of the pressure which is developed by the valve 10 for actuating the pressure responsive servomotor and the elevation precessing motor. The pressures thus developed are controlled primarily in accordance with the position of the handles 155, but these pressures are modified somewhat due to the rate of movement of the handles.

Rotation of the handles 155 and shaft 100 about a vertical axis causes the bracket 156 to rotate and, in turn, to rotate a segment of a bevelled gear 12 which, through a bevelled rack 13, actuates a shaft 14 carrying an arm 15 which is attached by a link 16 to a valve plunger 18 which controls the operation of the train rate pressure control valve 20. The elevation rate pressure control valve 10 and the train rate pressure control valve 20 are similar in construction and are adapted to develop pressures corresponding to the

axial displacement and rate of movement of the valve plungers 9 and 13 respectively.

Referring first to the valve 10, the block 157 is formed with a valve chamber 25 in which slides a sleeve 26. The plunger 9 slides axially within a bore in the sleeve 26. The sleeve 26 is provided with end surfaces forming with the respective ends of the chamber 25, pressure chambers 27 and 28 respectively. The chamber 27 is supplied with fluid from a constant pressure P_1 through a supply duct 29. The duct 29 contains an adjustable restriction formed by the adjusting screw 34, the end of which enters and partially closes the duct 29. The chamber 28 contains fluid under a pressure which is determined by the position and rate of movement of the sleeve 26 and which constitutes the elevation rate pressure P_e which is supplied by passage 30 to a duct 31. The end surfaces of the sleeve 26 are recessed to receive compression springs 32 and 33 which are seated within the chambers 27 and 28 respectively and serve normally to hold the sleeve 26 balanced in its mid-position, in which event the pressure in the chamber 28 will correspond to the pressure within the chamber 27. Chamber 28 communicates through a passage 40 with an annular chamber 41 formed in the plunger 9. Passages 42 and 43 in the sleeve 26 terminate at the plunger 9 on opposite ends of the chamber 41 so that these passages are normally closed by the plunger 9 when the plunger is in the center position as shown, but are respectively brought into communication with the chamber 28 through the chamber 41 and the passage 40 when the plunger 9 is shifted in one direction or the other from its center position. The passage 42 communicates with an annular chamber 45 formed around the periphery of the sleeve 26 and the passage 43 communicates with an annular chamber 46 similarly formed in the sleeve 26. The chamber 45 receives fluid under a constant pressure P_2 which is double the pressure P_1 and is supplied through a passage 47 in the block 157 which communicates with a supply duct 48 receiving fluid under the pressure P_2 from a suitable source. The chamber 46 contains fluid under a low or zero pressure P_0 which may constitute the intake pressure of the pump. The chamber 46 communicates through a passage 49 with a return duct 50 which leads to the supply reservoir of the pump.

The pressure P_1 is supplied by a P_1 generator valve 55 formed in the block 157 and comprising a chamber having a slide 56 provided with end surfaces 57 and 58 forming end chambers 59 and 60 respectively. The end surface 57 is formed with one half of the area of the end surface 58 so that when the slide 56 is in balanced position the pressure within the chamber 60 will be half that within the chamber 59.

The chamber 59 is connected to the passage 47 containing fluid under pressure P_2 by means of a passage 62. The slide 56 is formed with an annular chamber 63 which communicates through a passage 64 with the duct 29 to supply fluid under the pressure P_1 thereto. The annular chamber 63 communicates with the chamber 60 by means of a passage 65 in the slide.

The slide 56 is provided with a reduced diameter end portion 70 terminating at the surface 57 above mentioned and has an annular end surface 71 surrounding the end portion 70. This annular surface 71 forms with an intermediate end wall of the valve chamber an annular chamber 72. The annular chamber 72 communicates

through a passage 73 with the passage 49 containing fluid under return pressure P_0 . The passage 73 terminates at the slide 56 adjacent one end of the chamber 63 so that it is normally closed by the slide. A passage 75 communicates from the passage 62 to the valve chamber on the opposite end of the annular chamber 63 so that when the slide 56 is in its mid position, the passages 75 and 73 are both closed. The fluid pressures in the two end chambers 59 and 60 are then balanced and, due to the differences in area of the end surfaces, the pressure P_1 is generated at exactly one-half of the pressure P_2 . If the pressure P_1 should, however, vary from this amount, the pressure within the chamber 60 would likewise vary, thereby unbalancing the slide 56. If the pressure in the chamber 60 is reduced, for example, the pressure P_2 in the chamber 59 causes the slide 56 to move upwardly, thereby establishing communication from the passage 75 through the chamber 63 to the passage 65, thereby introducing fluid from the passage 75 into the passage 65 and increasing the pressure in the latter passage. The pressure will thus be built up until the pressures in the chambers 59 and 60 are again balanced at which time the slide 56 returns to its mid position and cuts off further fluid from the passage 75.

If, on the other hand, the pressure within the chamber 60 increases, the slide 56 will be forced downwardly establishing a communication from the passage 65 through the chamber 63 to the passage 73, thereby bleeding off some of the fluid within the passage 65 into the return duct 50. This will likewise continue until the pressure in the chamber 60 is reduced to P_1 , at which time a balance is again established. In this way the pressure in the passage 64 is maintained at exactly one-half of the pressure (P_2) in the duct 48.

In the operation of the elevation rate pressure control valve 10, beginning with the valve plunger 9 in the position shown, the pressure in the chamber 28 is exactly balanced against the pressure P_1 in the chamber 27. The elevation rate pressure P_e accordingly is the same as P_1 . If now the gunner rotates the handles 155 about the horizontal axis for producing a rate in elevation, the valve plunger 9 will be moved axially in one direction or the other. Assuming, for example, that the plunger 9 is moved upwardly, the chamber 41 is brought into communication with the passage 42 and fluid under pressure P_2 is supplied through the chamber 41 and passage 40 to the chamber 28, thereby increasing the pressure in the chamber 28 and disturbing the balance between the chambers 27 and 28. This increased pressure in the chamber 28 causes the sleeve 26 to move upwardly, thereby compressing the spring 32 and reducing the compression on the spring 33. This increase in pressure in chamber 28 causes the sleeve 26 to follow the plunger 9 upwardly until the sleeve has again reached a position relative to the plunger 9 at which the passage 42 is closed off. If the sleeve should move past this closing position, then communication would be established between the chamber 28 and the passage 43 which would remove some of the fluid from the chamber 28 to the return passage 49 and would correspondingly reduce the pressure on the lower end of the sleeve 26. When a new position of rest has been reached, the pressure within the chamber 28 plus the pressure of the spring 33 will exactly equal the pressure in the chamber 27 plus the pressure of the spring 32. The upward

displacement of the two springs, however, represents a net downward pressure on the sleeve 26 proportional to the displacement of the sleeve 26 from its mid-position. This downward pressure of the spring acting on the sleeve 26 is reflected as an increase in hydraulic pressure in the chamber 28 and in the pressure of the fluid P_e in the passage 30 and in the duct 31 which communicates therewith. This increase in hydraulic pressure is thus primarily proportional to the amount of vertical movement of the plunger 9 and the corresponding movement of the sleeve 26.

The restriction formed by the screw 34 in duct 29 restricts the flow of fluid from the chamber 27 and therefore the pressure in chamber 27 becomes higher than the normal P_1 pressure during upward movement of the sleeve 26. This higher pressure in chamber 27 results in a further increased pressure in the chamber 28 during upward movement of the sleeve 26. The effect of this transient change of pressure due to rate of movement of the handles 155 is to modify temporarily the generated pressure in a direction to apply a supplemental force to the pressure responsive servomotor to thereby overcome initial resistance to movement of the mechanism connected to the servomotor. When the generated pressure is used to apply precessing forces to a gyroscope the temporarily modified pressure acts to correct the position of the gyroscope. The effect of this modification of the precessing pressure is to aid the gunner in tracking the target when the gyroscope is used to control a line of sight, since it is not necessary for him to set up excessive precession rates in order to bring the line of sight on the target when it has gotten off for any reason. The relative amount by which the generated pressure is thus modified by the rate of movement of the handles 155 may be varied to suit the operator by adjusting the screw 34.

Movement of the plunger 9 in a downward direction reverses the above mentioned operation, establishing communication between the chamber 28 and the return passage 49 and thereby reducing the pressure in the chamber 28 to establish a pressure differential between the chambers 27 and 28 which causes the sleeve 26 to follow the plunger 9 downwardly. In this way the pressure within the chamber 28, and within the duct 31 which is supplied thereby, is caused to increase or decrease from the normal pressure P_1 by an amount determined by the direction, amount and rate of movement of the plunger 9 from its central position. The resultant pressure (P_e) established in the duct 31 accordingly represents the elevation rate (dE) which is to be set into the automatic computing mechanism and the direction and amount of the precessing force which is to be applied to the gyroscope.

The construction of the valve 20 is identical with that of the valve 10. The description will accordingly not be repeated. The parts of the valve 20 have, however, been given corresponding reference characters with the addition of a "t" to indicate that they apply to the train rate pressure generating valve. The chamber 28t communicates through the passage 30t with a duct 30 which carries fluid under pressure P_t which represents the train rate (dB_s) which is to be set into the automatic computing mechanism and the train precessing force to be applied to the gyroscope.

Rotational movement of the handles 155 and the shaft 100 about the vertical axis of the bracket

156 causes a corresponding axial movement of the plunger 18 which is followed by the sleeve 26t to generate the pressure P_t in the chamber 28t which varies from the pressure P_1 in a direction and by an amount determined by the direction, amount and rate of rotational movement of the bracket 156. This movement corresponds to the rate of train which the gunner desires to set into the control apparatus.

Pressure responsive servomotors

Referring now to Fig. 5, the rate amplifier servo block 210 is shown as containing train rate amplifier servo 220, elevation rate amplifier servo 221 and a P_1 generator valve 222 which is designed to generate a pressure P_1 corresponding to the pressure P_1 generated by the generator valve 55 of Fig. 1.

Inasmuch as the P_1 generator valve 222 is identical in construction with the P_1 generator valve 55, the corresponding parts have been given identical reference characters with the addition of a prime and will not be re-described. Fluid under pressure P_2 is supplied to the chamber 59' of the generator valve 222 from the P_2 supply duct 43 through a duct 207 and a passage 223. Return fluid at a pressure P_0 is fed to the return duct 50 from the valve chamber 72' through a passage 224 and a duct 205. Fluid under pressure P_1 is supplied from the valve chamber 60' to a passage 225.

The elevation servomotor 221 comprises a chamber formed in the block 210, containing a hollow piston 230 and a slide 231 which is mounted for axial movement within the piston 230. Chambers 232 and 233 are formed at the two ends of the piston 230. The chamber 232 is supplied with fluid at pressure P_1 through a passage 234 which communicates with the passage 225. Chamber 233 is supplied with fluid at a pressure controlled by the operation of the slide 231 through a passage 235 communicating with an elongated chamber 236 in the piston 230.

The slide 231 is acted upon at one end by the hydraulic pressure P_1 from the chamber 232 and at its other end forms a closure for a chamber 237 formed within the bore of the piston 230. The slide 231 is acted upon by two opposed springs 238 and 239. The spring 238 extends between one end of the slide 231 and a ring 240 attached to the piston 230 within the chamber 237. The spring 239 extends between the opposite end of the slide 231 and a pin 241 which is mounted in a fixed plate 242 forming an end closure for the chamber 232. The pin 241 is adjustable for varying the tension of the spring 239. The slide 231 is formed with a central annular chamber 245 which communicates through a passage 246 in the piston 230 with the chamber 236 and is thus in communication with the end chamber 233.

Fluid under pressure P_2 is supplied through a passage 250 from a passage 251, which communicates with the duct 207, to an elongated chamber 252 formed in the piston 230 and thence to a passage 253 which terminates adjacent the lower end of the chamber 245 and is normally closed by the slide 231.

Fluid at the pressure P_0 is returned from the valve 221 to the return duct 205 through a passage 255 in the block 210, which passage is connected to the slide 231 through a passage 256 in the block 210 leading to an elongated chamber 257 in the piston 230, thence through a passage 258 in the piston 230 which passage terminates

adjacent the upper end of the chamber 245 and is normally closed by the slide 231. The passages 253 and 258 are so arranged that one or the other is brought into communication with the chamber 245 when the slide 231 moves axially from its balanced position.

Fluid under pressure P_e is supplied from duct 31 (Fig. 1) through passage 260 in the block 210 to an elongated chamber 261 in the piston 230, thence through a passage 262 in the piston 230 which communicates with the chamber 237.

The link 366 which connects to the automatic computing apparatus is connected to the piston 230 and extends outwardly from the block 210.

The speed of response of the piston 230 to movements of the slide 231 is controlled by an adjusting screw 265 which extends into the passage 235 and controls the flow of fluid therethrough. Thus the controlling effect on the piston 230 of sudden changes in the controlling pressure due to the rate of movement of the handles 155 may be eliminated to a large extent by the restricted flow through the passage 235. A stop screw 266 carried by the piston 230 extends into the chamber 245 to limit the axial movement of the slide 231 relative to the piston 230.

Assuming that the pressure P_e equals the pressure P_1 , then the pressure within the chamber 237 will equal the pressure in the chamber 232 and the forces on the two ends of the slide 231 will be balanced. The slide will then take a position at which the forces due to the springs 238 and 239 are also balanced and the piston 230 will be in a position relative to the slide 231 such that the passages 253 and 258 are both closed, as shown in Fig. 5.

If now the pressure P_e is assumed to increase, the pressure in chamber 237 becomes greater than the pressure (P_1) in chamber 232 and the slide 231 is caused to move downwardly thereby increasing the tension of spring 238. This downward movement of the slide 231 opens the passage 253 to the chamber 245 and allows fluid under pressure P_2 to pass from the passage 250 through the chamber 245 and the passage 235 to the chamber 232. This increases the pressure in the chamber 232 and causes the piston 230 to move downwardly. This action continues until the downward movement of the piston 230 with respect to the slide 231 again centers the piston with respect to the slide and closes the passage 253. As the piston 230 thus follows the movement of the slide 231, the tension of the spring 238 is restored to normal. The slide 231 and the piston 230 move down together, except for the effect of the restriction in passage 235 caused by the screw 265, until the tension of the spring 239 is reduced by an amount corresponding to the increase in the pressure P_e in chamber 237. Since the pressure in the chamber 232 and tension of the spring 238 remain at their normal values, the slide 231 and the piston 230 assume a position where the increased effect of the pressure in chamber 237 tending to move the slide 231 down is neutralized by the reduced effect of the spring 239.

The sleeve 230 accordingly not only follows the movement of the slide 231, but, due to the large area of the end of the piston 230 as compared to the area of the ends of the slide 231, exerts an increased force which may be applied by the link 366 to the input of a computing mechanism such as that set forth in the patent application above identified. The ratio of the force exerted by the link 366 to that exerted upon the slide 231

may be varied as desired by changing the relative dimensions of the parts. Hence, the piston 230 may be caused to exert any necessary force upon the link 366 for actuating the computing mechanism.

As explained, the movement of the slide 231 and the piston 230 is proportional to the changes in pressure P_e . Hence the position of the link 366 represents the rate of elevation dE which is to be set into the computing mechanism.

It will be noted that the position taken by the link 366 is dependent only upon the pressure P_e and is not affected by leakage in the hydraulic system provided the leakage does not change the pressures. For any static position of the plunger 9 there is an exact corresponding position for the link 366 which is determined by the spring and hydraulic pressures only, provided of course the hydraulic system has sufficient capacity to keep the various passages and ducts full at the various pressures.

The elements of the train rate servomotor 220 are identical with those of the elevation rate servomotor above described and have accordingly been given the same reference characters with the suffix t . Fluid under pressure P_t is supplied to the train rate servomotor from the duct 80 through a passage 270 in the block 210. This causes a movement of the slide 231t which is proportional to changes in pressure P_t and a corresponding movement of the piston 230t which actuates the link 355 to introduce the rate of train dBs into the computing mechanism.

Although specific embodiments of the invention have been shown for purposes of illustration, it is to be understood that the invention is capable of various adaptations as will be readily apparent to a person skilled in the art. The invention is only to be limited in accordance with the scope of the following claims.

What is claimed is:

1. A pressure control valve comprising a valve housing, a sleeve in said housing forming fluid chambers at its two ends, spring means balancing said sleeve, means supplying fluid at a fixed intermediate pressure to one of said end chambers, a high pressure chamber, a low pressure chamber, a plunger movable in said sleeve and passages adapted to selectively connect said high pressure chamber or said low pressure chamber to the other of said end chambers for causing said sleeve to follow said plunger and to establish a pressure difference between said end chambers to counterbalance the unbalance of the spring pressures acting on the ends of said sleeve due to movement of said sleeve from its balanced position and means deriving a control pressure from said last chamber.

2. A pressure control valve comprising a valve housing, a sleeve in said housing forming fluid chambers at its two ends, springs biasing said sleeve to a mid-position, means supplying fluid at a fixed intermediate pressure to one of said end chambers, a high pressure chamber and a low pressure chamber in said sleeve, a plunger extending axially through said sleeve, a passage in said sleeve communicating with the other of said end chambers, a chamber in said plunger communicating with said passage, and passages in said sleeve normally closed by said plunger communicating with said high and low pressure chambers, said passages being adapted to be brought into communication with said plunger chamber and thence with said last end chamber by movement of said plunger relative to said

sleeve to supply said high or low pressure to said last end chamber to cause said sleeve to follow said plunger, the pressure in said last end chamber being determined by the unbalance of said springs produced by and displacement of said sleeve from its mid-position and means deriving a control pressure from said last chamber.

3. A pressure control valve comprising a valve housing, a sleeve in said housing forming fluid chambers at its two ends, means centrally biasing said sleeve, a source of supply of fluid at a fixed intermediate pressure, a passage connecting said source of supply of fluid to one of said end chambers, means restricting the flow of fluid through said passage effective to vary the pressure in said end chamber during movement of said sleeve, a high pressure chamber, a low pressure chamber, an adjustable plunger movable relative to said sleeve to selectively connect said high pressure chamber or said low pressure chamber to the second of said end chambers and means deriving a control pressure from said last end chamber.

4. A pressure control valve comprising a valve housing, a sleeve in said housing forming fluid chambers at its two ends, means centrally biasing said sleeve, a source of supply of fluid at a fixed intermediate pressure, a passage connecting said source of supply of fluid to one of said end chambers, means restricting the flow of fluid through said passage effective to vary the pressure in said end chamber during movement of said sleeve, a high pressure chamber, a low pressure chamber, an adjustable plunger movable relative to said sleeve, a passage in said sleeve communicating with the other of said end chambers, a chamber in said plunger communicating with said passage, and a pair of passages in said sleeve normally closed by said plunger and communicating with said high and low pressure chambers respectively, said passages being adapted to be brought into communication with said plunger chamber and thence with said last end chamber upon relative movement between said plunger and said sleeve

and means deriving a control pressure from said last end chamber.

5. A fluid pressure control valve comprising a source of high pressure fluid, a source of intermediate pressure fluid, a chamber for exhaust fluid, a valve housing, a sleeve in said housing forming fluid chambers at its two ends, means centrally biasing said sleeve, a passage connecting the source of intermediate pressure to one of said end chambers, means restricting the flow of fluid through said passage effective to vary the pressure in said end chamber during movement of said sleeve, an adjustable plunger movable relative to said sleeve, a port in said sleeve connected to said source of high pressure, a second port in said sleeve connected to said chamber for exhaust fluid, and a third port connected to the second of said end chambers, said ports being positioned to selectively connect the first or second ports to the third port upon relative movement between the plunger and the sleeve whereby the sleeve follows the movement of the plunger and the pressure generated in said second end chamber is responsive jointly to the pressure in said one end chamber and the biasing force acting on the sleeve due to displacement of the sleeve from its centrally biased position and means deriving a control pressure from said last end chamber.
